FREIGHT LOADING APPARATUS

Sulo Michael Nampa, Detroit, Mich., assignor to
 Evans Products Company, Detroit, Mich., a
 corporation of Delaware

Application February 12, 1945, Serial No. 577,374

18 Claims. (Cl. 105—369)

1

The present invention relates to improved loading apparatus for holding freight articles of different types in vehicles or storage spaces, and more particularly to improved equipment of this nature having certain parts which are built into or combined with a vehicle, such as an airplane, a ship, truck, trailer, railway freight car, or other storage space, and having certain other parts which are adjustably and variously co-operable with the built-in parts, the several parts of the equipment co-operating to hold (that is, for example, to brace, support or carry, space, wedge or provide shelves, partitions or bins for) a wide variety of freight articles. In certain of its aspects, the present invention provides improvements upon the invention described and claimed in applicant's copending application Serial No. 469,719, filed December 21, 1942, now abandoned, as a continuation in part of application Serial No. 434,357, filed March 12, 1942, now abandoned but replaced by copending application, Serial No. 740,330, filed April 9, 1947, as a continuation of said application, Serial No. 434,357 said application 740,330 now being Patent No. 2,519,846.

Objects of the present invention are to provide a freight-loading system of the above generally indicated type, which employs relatively light weight, readily maneuvered loading members, which may be economically manufactured and installed in the associated storage space and which may be readily adjusted to accommodate different loading conditions; to provide such a system employing tubular holding members, at least certain whereof comprise two or more telescopically related elements which are freely adjustable as to length and which may be fixed together in desired adjusted positions; to provide such a system embodying improved means for interconnecting a related pair of tubular members, said means including an adjustable jaw structure of improved construction; to provide such a system wherein the tubular members are of relatively thin-walled type and consequently are sufficiently elastic so that they can flex to accommodate distortions of the associated storage chamber due, for example, to the condition of the highway or road bed over which the associated vehicle is operating; and to provide such a system wherein the loading members are of relatively small cross section, adapting them to be readily threaded through meshed material, such as netting, which may be used in forming bulkheads and the like.

Other and more detailed objects of the invention appear in the following description and in the appended claims and in the drawings,

2

throughout the several views of which corresponding reference characters are used to designate corresponding parts, and in which:

Fig. 1 is a view in perspective of a storage compartment equipped in accordance with the invention;

Fig. 2 is a fragmentary view in vertical section, taken along the line 2—2 of Fig. 1;

Fig. 3 is a fragmentary view in vertical section, taken along the line 3—3 of Fig. 1;

Fig. 4 is a fragmentary view, partly in elevation and partly in section, of one of the improved loading members;

Fig. 4A is a fragmentary view showing the application of a jaw member to an outer telescopic tubular section;

Fig. 5 is a view in section taken along the line 5—5 of Fig. 4;

Fig. 6 is a view in horizontal section taken along the line 6—6 of Fig. 4;

Fig. 7 is a fragmentary view taken along the line 7—7 of Fig. 6;

Fig. 8 is a fragmentary view corresponding to Fig. 4 but showing the adjustable jaw structure in a different position of adjustment;

Fig. 9 is a view in elevation showing another loading arrangement which may be achieved with the loading members of the present invention; and

Fig. 10 is a fragmentary view illustrating how the present loading members may be used to co-operate with, for example, netting used in forming bulkheads.

It will be appreciated from a complete understanding of the present invention that, in their more generic aspects, the improvements thereof may be embodied in freight-loading systems of widely varying types, intended for use in connection with various types of storage chambers. The

improvements are particularly adapted to be embodied in relatively light weight, easily handled and adjusted loading members, having a degree of flexibility which particularly adapts them for use in connection with trucks and trailers. The disclosure of the invention herein with particular reference to such an application thereof is, however, to be taken in an illustrative and not in a limiting sense.

Referring to the drawings, particularly Figs. 1 through 8, the apparatus is built into a storage space or chamber which may be, for example, the body of a truck or trailer, which body is provided with a usual floor 10, side walls 12, and roof structure 14. To illustrate the adaptability of

the invention to irregularly shaped storage spaces,

the just-mentioned chamber is provided near one end with a stepped portion having an upper surface 16 and a vertical end surface 18. Specifically, Fig. 1 shows the interior of a trailer looking towards the front, in which 16-18 is the kick-up or raised portion which accommodates the fifth wheel assembly. A variety of differently dimensioned and shaped freight articles *f* are illustrated as being stacked in the storage space and as being held in place therein, in this instance, by bulkheads composed of a plurality of cross members 20.

In the illustrated embodiment, the freight-loading members comprise, in addition to the just-mentioned cross members 20, a plurality of horizontally arranged loading members or side rails 21, 22, and 23 and a plurality of vertically arranged loading members 24. In the preferred practice of the invention, the side rails are more or less permanently applied to the co-operating supporting parts of the chamber and may, in fact, constitute the structural members which form a part of, or act to reinforce, the chamber. As shown further, all of the members 20, 21, 22, 23, and 24 are tubular in form. Generically, a variety of tubular sections, such as square, hexagonal, or other noncircular sections may be employed, if relative rotation between the herein-after described telescopic sections is not required. Preferably, and as shown, the tubular members are cylindrical enabling both lengthwise and rotative movements between the telescoped sections. All of these members may be, and preferably are, formed of relatively light weight metal, such as aluminum or the like, having sufficiently resilient characteristics to enable them to flex to a reasonable extent so as to accommodate the structure to distortions of the freight chamber which are caused, for example, by uneven road conditions or the like. The vertical members 24 are secured to the side rails by the hereinafter described adjustable jaw structures which embrace, but do not completely surround, such side rails. Members 21, 22, and 23 are, accordingly, secured to the chamber walls by attaching elements which do not interfere with the application thereto of members 24 at any desired point therealong.

More particularly, as viewed in Figs. 1 and 2, each upper rail 21 is provided with a plurality of attaching brackets 30 which are distributed along the length thereof. Each bracket 30 is of generally Z shape, having a vertically disposed bight 32 and legs 34 and 36. Leg 34 is secured, along its lower edge 34a, to the upper surface of the co-operating rail 21. With this relation, the bight 32 is disposed above and out of the way of the body of the rail, so that it does not interfere with movement along the latter of the jaws 36 associated with the co-operating vertical members 24. The remaining leg 36 extends downwardly somewhat with respect to the bight 32 and is adapted for connection, as by one or more bolts 38, to the wall structure 12. As will be appreciated, the above described bracket structure is particularly suitable in cases where the rails 22 are located somewhat below the roof structure or somewhat above the floor structure.

In the present instance, the lower rails 22 and 23 are secured directly to the sub-floor or framing structure underneath the wear surfaces designated 10 and 16, and so occupy recesses or channels 25 between the chamber walls and the side of such wear surfaces or heavy duty flooring 10-16. The jaws 36 require little radial or lateral clearance in operation, so that the channels 25

may be relatively narrow. As illustrated, rails 22-23 are only partly recessed. If desired they may be completely recessed to realize the maximum of usable freight loading volume, and to prevent injury to or interference between the load and such recessed rails. As shown, the rails 22 and 23 are secured in place by passing bolts such as 40 through the corresponding supporting surface 41 as well as through the structural member 43 (Fig. 3).

It will be observed that the vertical spacing between rails 21-22, on the one hand, and rails 21-23, on the other hand, are different. There may be cases, also, in which members 21-22-23 may be nonparallel, as in accommodating irregular vehicle shapes. The hereinafter described telescopic feature of uprights 24 is peculiarly advantageous in permitting the use of interchangeable parts to accommodate a wide range of spacings.

The above discussed lack of parallelism or different spacing arises from the design of the vehicles or other storage space. In addition, as a practical matter, there are static errors or permanent manufacturing inaccuracies whereby two elongated spaced apart surfaces will not be truly parallel. Also, similar conditions arise dynamically due to the weaving of the vehicle in transit. In all of these cases, the telescopic feature of members, such as 23-24 (and in some cases, even rails 21-22-23) is of practical value.

Structurally, the vertical members 24 and the cross members 20 may be identical with each other and, in fact, may be used interchangeably since the lengths thereof are readily adjustable. This interchangeability is of substantial practical importance to the manufacturer in that it reduces the number of different parts which he must arrange to produce; and to the user in that he does not need to exercise care in selecting the proper part for an upright or cross bar, since he may, with a given number of parts, provide for more different loading conditions. Stated otherwise, a smaller number of parts will suffice to adequately equip a vehicle. A description of, for example, one of the members 25 will consequently serve as a description of the members 24.

Referring particularly to Figs. 4 through 8, each number 20 is made up of two telescopically related tubular portions 20a and 20b, both being illustrated as of circular section. The fit between these members is such that they may be freely slid lengthwise and rotated relative to each other. A limit to lengthening adjustment is afforded in this instance by providing an end plate 50 which is secured at the end of each inner section. Each plate 50 is apertured as indicated at 52, so as to loosely pass a connecting rod 54. Each rod 54 also passes loosely through a second motion-limiting plate 56 which may be secured in any suitable way within the body of the cooperating outer member 20b. With this relation, it will be appreciated that a limit to lengthening movement is reached when plates 50 and 56 are spaced apart far enough to encounter the nuts 58 and 60, or other stops, formed on rod 54. A limit to collapsing movement on the other hand is afforded when plates 50 and 56 abut each other. It will be appreciated that, by locating each plate 56 relatively near the outer end of each outer section 20b and giving the rod 54 a length approximately equal to the length of section 20b, a range of adjustment approximately equal to the length of the section 20b may be provided. Such a range of adjustment makes it readily possible to use

members 20 and 24 interchangeably as verticals and as cross members.

In assembling the two sections 20a and 20b together, it will be understood that plate 50, with rod 54 already fitted thereto, may first be secured in the end of section 20a. Thereafter the assembly comprising section 20a, plate 50, post 54 and plate 56 may be advanced into the outer section 20b, and pushed therealong until plate 56 reaches the desired position lengthwise of section 20b. With the parts thus properly located, the plate 56 may be secured in place within section 20b as by spot welding, passing one or more mounting studs through corresponding ones of openings 60 into plate 56, or otherwise.

In order to enable end-to-side connections between individual vertical and cross members, each member 20 is provided throughout its length with a plurality of attaching means. As shown, these attaching means take the form of relatively small, slightly elongated openings 60 which pass through the walls of each section 20a and 20b. The hereinafter described jaws 36 are arranged to co-operate with circumferentially spaced pairs and groups of the attaching openings. Specifically, each section 20a and 20b is provided with four rows of equiangularly spaced openings 60 which enable the jaws to be connected thereto at any one of four positions spaced approximately 90° apart. As noted below, the slightly elongated shaping of the openings facilitates the application of the jaws 36 to the members 20. Also such shaping enables some canting of each jaw with respect thereto. Considering Fig. 1, for example, this canting permits members 20 to be canted somewhat in both horizontally and vertically disposed planes. The canting operations serve to accommodate the structure to irregular loads or to loads which, for example, do not extend entirely across the vehicle, all as will be understood.

Each jaw 36 is made up, in the illustrated embodiment, of a pair of relatively movable, arcuately shaped jaw elements 62 and 64. The inner or bearing surfaces of these jaws are struck on radii approximately equal to the outside diameter of each inner section 20a, so that when they embrace such an inner section (Fig. 4) they snugly fit the outer surface thereof. Each jaw element is provided on its inner surface with a plurality of attaching means which, as shown, take the form of substantially circular bosses 66. These bosses project radially inwardly a distance approximately equal to the wall thickness of each outer section 20b, so that when the jaws (Fig. 8) are fitted over such outer section, the bosses will not be interfered with by an imperforate portion of the periphery of the inner section 20a. Thus the jaws 36 can cooperate with an outer section 20b independently of whether its openings 60 are aligned with the openings 60 in the cooperating section 20a.

Each jaw element 62 is secured as by spot welding, as indicated as 70, to a rearwardly extending body portion 72. In the case of a jaw at the end of an inner section 20a, each jaw portion 72 may, and preferably does, constitute a semicircular extension of such section 20a defined by cutting away the latter along the radial line 74 and along the axial line 76. In the case of a jaw formed in the end of an outer section 20b, the semicylindrical body portion 72 may be provided at the end of a tubular extension 73 which may be welded or otherwise secured within the extreme end portion of the section 20b, as shown in Fig. 4A.

Near its inner end, each body 72 is provided with a diametrically extending rib or boss 78 which may be secured in place therein as by welding, as indicated at 80.

Each co-operating jaw member 64 is provided with a rearwardly extending body portion 82, which may be and preferably is of semi-cylindrical form. Each body portion 82 is provided at its outer end with a pair of bearing bosses 84, the spacing wherebetween, as viewed in Fig. 5, is sufficient to snugly but freely receive the previously mentioned boss 78. Bosses 78 and 84 are provided with aligned apertures which receive a pivot pin 86, which may have a drive fit within either the boss 78 or the two bosses 84. Pin 86 thus serves to pivotally interconnect the two jaw elements 62 and 64, and allows sufficient spreading thereof to enable them to be freely passed over either an inner or an outer section 20a or 20b.

An important feature of the present invention resides in the provision of means to lock the jaw members together when fitted over either an inner or an outer section. As illustrated, this locking is accomplished by a sleeve 90 which is slideable lengthwise of the jaw assembly from the locked position shown in Figs. 4 and 8 to a retracted position spaced sufficiently far from the jaw elements to permit the necessary pivoting of the latter. Preferably, and as shown, detent means are provided to releasably hold the sleeve 90 in its locking position. The detent structure comprises a ball 92 which is biased outwardly by a spring 94 fitted in a recess provided in the boss 78. The material surrounding the ball is peened over slightly after insertion of the latter to prevent escape of the ball from the detent pocket, in accordance with familiar practice.

In order to enable it to lock the jaw elements in either of the positions of Figs. 4 and 8, sleeve 90 is provided with an axially extending radially projecting recess or groove 96, which co-operates with a correspondingly shaped rib 98 formed on the body 82 associated with jaw element 64. Sleeve 90 is both turnable and slideable relative to the jaw assembly. Thus, when the jaws are fitted over an inner section 20a, sleeve 90 can be turned to the rotative position shown in Fig. 5, in which rib 98 is out of registry with groove 96. When so positioned, sleeve 90 obviously holds the jaw members relatively close together, forcing the bosses 66 into the openings 60 in the inner section 20a. On the other hand, when the jaw members are fitted over an outer section 20b, sleeve 90 is first turned to a rotative position in which rib 98 is lined up with groove 96 and thereafter sleeve 90 is slid lengthwise of the jaw assembly from the retracted position to the locking position. The proportioning of the rib 98 and the groove is such, as will be understood, as to enable the sleeve 90 to hold the jaws in relatively snug engagement with the surface of an outer section 20b.

It will be noticed that when the jaws 62 and 64 are separated, the holding elements 66 on at least jaw 64 move in an arcuate path, having the pin 86 as a center. This arcuate movement is not truly radial with respect to the co-operating member 20a or 20b. The oval shaping of the holes 60, however, readily permits such non-radial movement and enables the jaw structures to be freely separated from the co-operating load-members.

Referring again to Fig. 1, it will be appreciated that the fixed rails 22 are provided with inner

and outer rows of attaching openings 60 for cooperation with the jaws 36 and associated vertical members. If desired, additional rows of openings 63 may be provided in the members 22 in angularly spaced relation to the just-mentioned openings, thereby permitting members 20 or 24 to be secured thereto in different angular positions, and in fact making members 22 identical with members 20 and 24 or at least enabling them to be formed of the same tubing, either the larger or smaller size and with the same holes; thereby giving rise to the advantages mentioned above in connection with the interchangeability of parts 20—24. Moreover, it will be appreciated that it is within the purview of the invention to secure members 22 to the vehicle by readily detachable or removable fastening means, which may be, for example, in the form of studs such as 40. In cases where members 22 are detachably secured, they may be telescopically extensible lengths identical with members 20 or 24, without jaw structures. Alternatively, members 20 or 24 may be detachably secured to the vehicle and serve as side rails with their jaws thereon. Further, such a side rail may be formed of either an inner or an outer telescopic section, or of both such sections, of members 20—24, detached or pulled apart. In general, the only members which are secured to members 22 are the vertically extending members 24. Consequently, the two inner and outer rows of openings 60 are usually sufficient.

Also, if desired, more than four rows of openings may be provided in the elements which make up the members 20 and 24. As a general rule, however, the indicated four rows are found to be sufficient, particularly in view of the canting relation which is permitted by the elongated character of the openings 60 and by the somewhat loose fit between the surfaces of the jaw elements and the surfaces of the inner and outer telescopically related sections.

It will be evident that various combinations of vertical, horizontal, and diagonally extending members may be made up from the members such as 20 and 24, to accommodate different freight-loading situations. In Fig. 1 the character of the freight is such that horizontal bulk-head elements are best adapted to hold the freight in place. In Fig. 9, on the other hand, the character of the load is such that the bulk-head elements are better adapted to extend vertically. In Fig. 10 again, the character of the freight load may be such as to make it desirable to utilize a heavy net 100, formed of rope or the like. This net may be held in place by threading the members such as 20 and 24 therethrough.

Again, it will be understood that, if desired, members such as 20 and 24 may be arranged so as to define decking, bins, partitions, and the like, in the manner described in said copending application. In such latter event, for example, members 24 may be arranged at intervals along the length of the chamber to define side bays, short members 20 may extend between adjacent uprights and serve as bay members, and further members 20 may extend across the space and be supported by such bay members. Moreover, cross members such as 20 may be connected directly between side rails 22, and between rails 21—23 in the event the recessing of the latter permits or is eliminated.

Although only several embodiments of the invention have been described in detail, it will be appreciated that various modifications in the

form, number and arrangement of parts may be made without departing from the spirit and scope of the invention.

What is claimed is:

- 5 1. In a freight loading system for a storage space, the combination of a pair of vertically spaced generally horizontally extending tubular members fixed at each side of said space, at least a pair of generally vertically extending tubular members, each vertical member extending between and being adjustably secured to the horizontal members of the corresponding pair for adjustment lengthwise of the latter, and one or more tubular members extending between and adjustably secured to said pair of vertical members for adjustment lengthwise of the latter, at least certain of said tubular members comprising a pair of telescopically related tubular elements which are slidable lengthwise of each other, and at least certain of said tubular members having means adjacent the ends thereof which embrace others of said members to effect said adjustable securing.
- 15 2. In a freight loading system for a storage space, the combination of at least a pair of elongated tubular loading members adjustably supported at respectively opposite sides of said space, and at least one tubular member extending across said space and being adjustably supported adjacent its ends by said loading members for adjustment lengthwise of the latter, at least certain of said members comprising a pair of telescopically related tubular elements which are slidable lengthwise of each other, and said one tubular member having means adjacent its ends which embrace said pair of members to effect said adjustable support of said one member.
- 25 3. The system of claim 2 wherein said first-mentioned members are adjustably supported adjacent their ends by vertically spaced supporting means provided therefor.
- 30 4. In a freight loading system for a storage space, the combination of a pair of tubular members supported in vertically spaced relation to each other, and at least one generally vertically extending tubular member extending between and adjustably supported adjacent its ends by said first-mentioned members for adjustment lengthwise of the latter, at least certain of said members being constituted by a pair of telescopically related tubular elements slidable lengthwise of each other, and said one tubular member having means adjacent its ends which embrace said pair of members to effect said adjustable support of said one member.
- 35 5. In a freight loading system for a storage space, the combination of a pair of vertically spaced generally horizontally extending members positioned at each side of said space, at least a pair of generally vertically extending members, each vertical member extending between and being adjustably secured to the horizontal members of the corresponding pair for adjustment lengthwise of the latter, and one or more cross members extending between and adjustably supported by said pair of vertical members for adjustment lengthwise of the latter, at least certain of said horizontal, vertical and cross members including heads at the ends thereof and having body portions which cooperate with said heads to effect said securing and support, said heads and said body portions being substantially alike so that at least certain of said horizontal, vertical and cross members are interchangeable with each other so that, for a given total number of
- 40 6. In a freight loading system for a storage space, the combination of a pair of vertically spaced generally horizontally extending members positioned at each side of said space, at least a pair of generally vertically extending members, each vertical member extending between and being adjustably secured to the horizontal members of the corresponding pair for adjustment lengthwise of the latter, and one or more cross members extending between and adjustably supported by said pair of vertical members for adjustment lengthwise of the latter, at least certain of said horizontal, vertical and cross members including heads at the ends thereof and having body portions which cooperate with said heads to effect said securing and support, said heads and said body portions being substantially alike so that at least certain of said horizontal, vertical and cross members are interchangeable with each other so that, for a given total number of
- 45 7. In a freight loading system for a storage space, the combination of a pair of vertically spaced generally horizontally extending members positioned at each side of said space, at least a pair of generally vertically extending members, each vertical member extending between and being adjustably secured to the horizontal members of the corresponding pair for adjustment lengthwise of the latter, and one or more cross members extending between and adjustably supported by said pair of vertical members for adjustment lengthwise of the latter, at least certain of said horizontal, vertical and cross members including heads at the ends thereof and having body portions which cooperate with said heads to effect said securing and support, said heads and said body portions being substantially alike so that at least certain of said horizontal, vertical and cross members are interchangeable with each other so that, for a given total number of
- 50 8. In a freight loading system for a storage space, the combination of a pair of vertically spaced generally horizontally extending members positioned at each side of said space, at least a pair of generally vertically extending members, each vertical member extending between and being adjustably secured to the horizontal members of the corresponding pair for adjustment lengthwise of the latter, and one or more cross members extending between and adjustably supported by said pair of vertical members for adjustment lengthwise of the latter, at least certain of said horizontal, vertical and cross members including heads at the ends thereof and having body portions which cooperate with said heads to effect said securing and support, said heads and said body portions being substantially alike so that at least certain of said horizontal, vertical and cross members are interchangeable with each other so that, for a given total number of
- 55 9. In a freight loading system for a storage space, the combination of a pair of vertically spaced generally horizontally extending members positioned at each side of said space, at least a pair of generally vertically extending members, each vertical member extending between and being adjustably secured to the horizontal members of the corresponding pair for adjustment lengthwise of the latter, and one or more cross members extending between and adjustably supported by said pair of vertical members for adjustment lengthwise of the latter, at least certain of said horizontal, vertical and cross members including heads at the ends thereof and having body portions which cooperate with said heads to effect said securing and support, said heads and said body portions being substantially alike so that at least certain of said horizontal, vertical and cross members are interchangeable with each other so that, for a given total number of
- 60 10. In a freight loading system for a storage space, the combination of a pair of vertically spaced generally horizontally extending members positioned at each side of said space, at least a pair of generally vertically extending members, each vertical member extending between and being adjustably secured to the horizontal members of the corresponding pair for adjustment lengthwise of the latter, and one or more cross members extending between and adjustably supported by said pair of vertical members for adjustment lengthwise of the latter, at least certain of said horizontal, vertical and cross members including heads at the ends thereof and having body portions which cooperate with said heads to effect said securing and support, said heads and said body portions being substantially alike so that at least certain of said horizontal, vertical and cross members are interchangeable with each other so that, for a given total number of
- 65 11. In a freight loading system for a storage space, the combination of a pair of vertically spaced generally horizontally extending members positioned at each side of said space, at least a pair of generally vertically extending members, each vertical member extending between and being adjustably secured to the horizontal members of the corresponding pair for adjustment lengthwise of the latter, and one or more cross members extending between and adjustably supported by said pair of vertical members for adjustment lengthwise of the latter, at least certain of said horizontal, vertical and cross members including heads at the ends thereof and having body portions which cooperate with said heads to effect said securing and support, said heads and said body portions being substantially alike so that at least certain of said horizontal, vertical and cross members are interchangeable with each other so that, for a given total number of
- 70 12. In a freight loading system for a storage space, the combination of a pair of vertically spaced generally horizontally extending members positioned at each side of said space, at least a pair of generally vertically extending members, each vertical member extending between and being adjustably secured to the horizontal members of the corresponding pair for adjustment lengthwise of the latter, and one or more cross members extending between and adjustably supported by said pair of vertical members for adjustment lengthwise of the latter, at least certain of said horizontal, vertical and cross members including heads at the ends thereof and having body portions which cooperate with said heads to effect said securing and support, said heads and said body portions being substantially alike so that at least certain of said horizontal, vertical and cross members are interchangeable with each other so that, for a given total number of

members, various loading combinations can be provided.

6. In a freight loading system, an elongated member of a varying width having a plurality of holding means disposed along its length and a cooperating elongated member to be transversely secured to said first member in selected positions therealong, said second elongated member having on its ends a pair of relatively spreadable jaw elements disposed to embrace the width of said first member and cooperate with said holding means, and retaining means movable from a retracted position in which it does not interfere with said spreading to either a first holding position in which it permits one degree of spread of said elements or a second holding position in which it permits a different degree of such spread.

7. In a freight loading system, an elongated member of a varying width having a plurality of holding means disposed along its length and a cooperating elongated member to be transversely secured to said first member in selected positions therealong, said second elongated member having on its ends a pair of relatively spreadable jaw elements disposed to embrace the width of said first member and cooperate with said holding means, and control means for the jaw elements capable of two adjusting movements, one said movement freeing said jaw elements of restraint thereby and the other movement serving to variably control the degree to which said jaw elements are enabled to spread.

8. In a jaw structure for use in a freight loading system to releasably connect one freight loading part to a cooperating part, the combination of a pair of relatively spreadable jaw elements disposed to embrace a cooperating part, means connecting said elements to said first-mentioned part, and retaining means movable from a retracted position in which it does not interfere with said spreading to a holding position in which it restrains such spreading, said cooperating part having a plurality of rows of holding means distributed around the body thereof, and said jaw elements having cooperating holding means disposed to cooperate with holding means in spaced ones of said rows.

9. In a freight loading system, the combination of a supporting member comprising a pair of telescopically related elements slidable lengthwise relative to each other, and a supported member adjustably securable to the supporting member, said supported member being provided with an adjustable jaw structure which can be fitted over the supporting member from the side thereof, and means for releasably securing the jaw structure to either an inner or outer element of said supporting member.

10. The system of claim 9 wherein said jaw structure embraces but does not completely surround said supporting member.

11. The system of claim 9 wherein said jaw structure and supporting member are provided respectively with interlockingly engageable holding elements disposed to be retained in interlocking engagement by said securing means.

12. The system of claim 9 wherein the supporting member is provided with a succession of lengthwise distributed openings in each element thereof, and wherein said jaw structure is provided with holding means disposed to lockingly enter said openings, said holding means being of such length that they enter said openings to a depth not substantially exceeding the wall

thickness of the outer one of said telescopically related openings.

13. In a freight loading system, the combination of an elongated supporting member, an elongated loading member supported thereby, said loading member having a jaw structure, comprising a pair of spreadable jaw elements, which can be fitted over the supporting member from the side thereof, said jaw elements embracing but not surrounding said supporting member so that a gap is left between the jaw elements at one side of the supporting member, and means for securing the supporting member to associated supporting structure, said securing means being receivable in said gap whereby said jaw structure may be moved along said supporting member past said securing means.

14. The system of claim 13 wherein said supporting member and said jaw structure include interlockingly engageable holding means which when engaged secure said jaw structure against movement along said supporting member, and said jaw structure is provided with retaining means for controlling spreading of said jaw elements and for controlling engagement between said holding means.

15. In a freight loading system the combination of a pair of spaced tubular supporting members each having a plurality of peripherally spaced longitudinally extending rows of attaching openings, a tubular member extending between and supported by the spaced members, said supported member having a releasable jaw structure at each end, each jaw structure comprising a pair of jaw elements carried by said member and connected thereto for pivotal movement with respect to each other, said jaw elements when spread apart being fittable over the corresponding supporting member from the side thereof, each jaw element having holding means disposed to enter the openings in a corresponding said row, and an adjusting part movable on each jaw structure from a position in which it permits said spreading to a position in which it restrains the spreading and holds the holding means in said openings.

16. The system of claim 15 wherein at least one of said supporting members comprises a pair of telescopically related tubular elements each having peripherally spaced rows of openings therein, and wherein said adjusting part includes means selectively positionable on said jaw structure so that it can restrain said jaw structure in holding relation to either of one of said telescopically related elements.

17. In a freight loading system, a pair of spaced generally circular supporting members each being of elongated form and each having at least one row of recesses extending therealong, each recess opening through the outer surface of the wall of the corresponding member, each recess being of oval form with its major axis extending peripherally of the corresponding member, and a cooperating loading member extending between and supported by said first-mentioned members, said cooperating member having at each end a spreadable jaw which embraces the corresponding first-mentioned member, each jaw structure having one or more holding elements disposed to be received in corresponding ones of said recesses.

18. The structure of claim 17 wherein each first member is composed of a pair of telescopically related tubular sections, each section being provided with said recesses, and wherein said jaw

11

structures are adapted to interlockingly embrace either an inner or outer said telescopic section.
SULO MICHAEL NAMPA.
